UNITED STATES PATENT OFFICE.

SAMUEL A. FRENCH, OF NEW YORK, N. Y.

BUTTON.

No. 895,740.

Specification of Letters Patent.

Patented Aug. 11, 1908.

Application filed June 3, 1907. Serial No. 376,983.

To all whom it may concern:

Be it known that I, SAMUEL A. FRENCH, a citizen of the United States, and resident of the borough of Manhattan, in the city and 5 State of New York, have invented a new and useful Improvement in Buttons, of which the following is a specification.

My invention relates to buttons and more particularly to a button capable of being secured against displacement in the position in 10 which it is used.

I have chosen to illustrate my invention, a type of button suitable for use in connection with collars and cuffs.

15 In the accompanying drawings, Figure 1 is a view of the button with the fastening device swung into its open position ready to apply the button, Fig. 2 is a view showing the fastening in its closed position, Fig. 3 is a 20 section in the plane of the line A—A of Fig. 2, and Figs. 4, 5, 6 and 7 are face views of modified forms of fastening.

In all the forms illustrated, the fastening is made of resilient material capable of springing 25 past the head of the button into and out of contact with its stem and is pivotally secured to the base of the button to be swung into and out of fastening position relative thereto.

30 The base of the button is denoted by 1; its stem by 2 and its head by 3.

On the base 1 there is fixed a socket 4 for the reception of the end of the fastening, the latter being conveniently formed of spring 35 wire.

In the form shown in Figs. 1, 2, 3, the end of the fastener which is received in the socket is denoted by 5; the end which engages the button is denoted by 6 and a single bend 7 is 40 located between the socket end and free end in order to bring the free end in position to engage the stem of the button.

The fastener may be held in its socket by giving its socket end a slight turn and the 45 free end may be made smooth by turning it in the form of a small bend or eye. This feature may also add to convenience in receiving the finger of the operator to bring the free end into and out of position to effect a fastening.

In operation, the head of the button having been passed through the article to be fastened, as through a button hole therein, the fastening device may be swung over into engagement with the head of the button and

by pressure, the fastening device may be sprung outwardly sufficient to pass the head when it will, of its own resiliency, spring back into engagement with the stem and thus form a secure lock against the unintentional 60 displacement of the button.

When it is desired to remove the button, the free end of the fastening device may be sprung outwardly sufficient to pass the head of the button and the fastening device then 65 swung over into open position to permit the button to be withdrawn through the button hole.

In the form shown in Fig. 4, the fastening device is given a double bend, the bends of 70 the device being denoted by 8 and 9, before it passes into position to engage the head of the button. This form admits of increased resiliency to the fastening device while the socket may be located quite near the stem of 75 the button on the base thereof.

In the form shown in Fig. 5, the fastening device is given a double bend, the bends being noted by 10 and 11, and the free end, instead of going over the side of the head of 80 the button furthest from the socket, is intended to spring inwardly and pass that side of the head of the button nearest the socket, the free end of the spring still resting when in locked position against the stem of the 85 button.

In the form shown in Fig. 6, the fastening device is given two bends denoted by 12 and 13, and its free end springs over the outer 90 side of the head of the button but extends in the opposite direction from that shown in Fig. 1.

In the form shown in Fig. 7, the fastening device is given three bends, denoted by 14, 15, 16, its free end springing over the outer 95 edge of the button and extending in the same direction to that shown in Fig. 1.

In all the forms presented, the base of the button forms the support for the fastening device and thus serves a double function 100 of preventing the button from passing outwardly through the button hole and at the same time forms a support for the fastening device and coacts with it to lock the button against displacement in either an outwardly 105 or inwardly direction when the fastening device is swung into operative position.

The device has the advantage of a smooth surface not liable to chafe the flesh of the wearer and the device furthermore is hidden 110

from view when the second part of the article to be buttoned is passed into position over the head of the button.

While I have shown several different forms 5 which the fastening device may assume, it is obvious that other forms might be resorted to within the scope of the appended claim without departing from the spirit and scope of my invention; hence I do not wish to 10 limit myself strictly to the structure herein shown and described, but

What I claim is:—

A button comprising a base, a stem, a head and a resilient fastening device consisting of 15 a single part extending at one end along and having a rocking movement in a socket on

the base at one side of the stem, the body of the fastening being curved to bring the free end of the fastening into sidewise position underneath the head and the said fastening 20 device being free to yield downwardly along the stem while having a normal tendency to spring against the stem underneath the head.

In testimony, that I claim the foregoing as my invention, I have signed my name in 25 presence of two witnesses, this 31st day of May 1907.

SAMUEL A. FRENCH.
